Primary Examiner — John R Yeh*(74) Attorney, Agent, or Firm* — Troutman Pepper
Hamilton Sanders LLP; Ryan A. Schneider; Chris N.
Davis(57) **CLAIM**

The ornamental design for a reindeer mounting clip, as shown and described.

DESCRIPTION

FIG. 1 is a perspective view of our new design for a reindeer mounting clip;

FIG. 2 is a front elevation view thereof;

FIG. 3 is a rear elevation view thereof;

FIG. 4 is a left side elevation view thereof;

FIG. 5 is a right side view thereof;

FIG. 6 is a top plan view thereof; and,

FIG. 7 is a bottom plan view thereof.

The broken lines depict portions of the reindeer mounting clip that form no part of the claimed design.
